[57] CLAIM

The ornamental design for a softcap respirator hood, substantially as shown and described.

DESCRIPTION

FIG. 1 is a perspective view of the softcap respirator hood showing my new design being worn, the dotted line portions of the drawing being for illustrative purposes only;

FIG. 2 is a side view of the softcap respirator hood of FIG. 1 viewed from the left side thereof, the other side being a mirror image of the side illustrated;

FIG. 3 is a front view of the softcap respirator hood of FIG. 2;

FIG. 4 is a rear view of the softcap respirator hood of FIG. 2; and

FIG. 5 is a top plan view of the softcap respirator hood of FIG. 2.
